(57) **CLAIM**

The ornamental design for a two-segment proximity payment device assembly, as shown and described.

DESCRIPTION

FIG. 1 is a perspective view of a two-segment proximity payment device assembly showing our new design;

FIG. 2 is a top plan view thereof;

FIG. 3 is a front elevational view thereof; and,

FIG. 4 is a side elevational view thereof.

The left and right side elevational views of the two-segment proximity payment device assembly are identical. The bottom plan view of the two-segment proximity payment device assembly is identical to FIG. 2. The rear elevational view is a mirror image of FIG. 3.
